OR

D 13,412

EX

No. 13,412

Nov. 14, 1882

UNITED STATES PATENT OFFICE.

JOHN L. POPE, OF CLEVELAND, OHIO.

DESIGN FOR A WEAR-IRON.

SPECIFICATION forming part of Design No. 13,412, dated November 14, 1882.

Application filed August 2, 1882. Term of patent 14 years.

To all whom it may concern:

Be it known that I, JOHN L. POPE, of Cleveland, in the county of Cuyahoga and State of Ohio, have invented and produced a new and original Design for Wear-Irons, of which the following is a specification, reference being had to the accompanying drawing, forming part thereof.

My invention relates to a design for wear-irons that are used on carriages and other vehicles; and it consists in the novel external configuration thereof, as well as in a feature of ornamentation of the upper surface of the article, as will be hereinafter more particularly described and claimed.

As will be seen in the accompanying engraving, one end, *a*, of the iron is longer than the other, *b*, and is inclined inwardly until it meets the long part or shank *c*, which latter extends along until the short end *b* of the iron

is met. From both ends of the iron project lugs or ear-pieces *e*, provided with holes, at which point the article is attached to the body or other portion of the vehicle. I have ornamented the upper face of the iron by grooving centrally, and forming thereby ribs *f* and *h*.
25

What I claim as of my invention, and desire to secure by Design Letters Patent, is—

1. A wear-iron having substantially the form shown and described.
  2. A wear-iron of the form shown, centrally grooved and ribbed, substantially as illustrated and described.
- 30

In witness whereof I have hereunto set my hand this 22d day of June, 1882.

JOHN L. POPE.

In presence of—

CHAS. W. MOSES,
C. M. COPP.
